UNITED STATES PATENT OFFICE.

WALTER S. FREEBURG, OF MILWAUKEE, WISCONSIN, ASSIGNOR, BY MESNE ASSIGNMENTS, TO THE FISK RUBBER COMPANY, OF CHICOOPEE FALLS, MASSACHUSETTS, A CORPORATION OF MASSACHUSETTS.

STRETCHING DEVICE.

Application filed August 19, 1921. Serial No. 493,731.

My invention relates to stretching devices and the principal object of my invention is to provide an improved device of this type. In the drawings accompanying this specification and forming a part thereof I have shown, for purposes of illustration, one embodiment of my invention in which the device is utilized to impart stretch to fabric which is being rubberized and is therefore combined with a rubberizing calender. In these drawings Figure 1 represents a general view of the device, Figure 2 is a detail view of the mounting of the upper tensioning bar, and Figure 3 is a plan view of the circuit control.

The device herein shown comprises an upper calender roll 11, a center calender roll 12, and a lower calender roll 13, all of which may be of any desired construction. The driving gears have been omitted in the interest of clearness but may take any conventional form, examples being shown in the patents to Gwozdz 1,402,160, June 3, 1922, and Midgley 1,500,679, July 8, 1924. The rolls 12 and 13 are adapted to receive between them the fabric strip 14.

Positioned just ahead of the calender rolls is a tensioning device 15 comprising a pair of rotatable bars 16 adapted to lie beneath the fabric strip and a preferably non-rotatable bar 17 adapted to lie above the fabric strip and to cooperate with the bars 16 to retard the movement of the fabric and thereby place under tension the fabric between the calender rolls and the tensioning device and in this manner impart stretch to the fabric. The bar 17 is supported by a pair of screw-threaded rods 18 which engage screw-threaded blocks 19 carried by the bar 17 and each rod 18 carries at its upper end a bevel gear 20 adapted to cooperate with a bevel gear 21 mounted on a cross-shaft 22 so that rotation of one of the rods 18 will cause like rotation of the other rod 18. One of the rods 18 also carries at its lower end a bevel gear 23 which meshes with a cooperating bevel gear 24 carried by a shaft 25 driven by a motor 26. The motor 26 may be a three-phase induction motor connected to a line 27 by means of a wire 28 running directly to the line and a pair of wires 29 and 30 running to the line through the electromagnetic reversing switch 31 operated by means of solenoids 32 and 33 and held normally in mid-position by centering springs 34. It will be obvious from the above description that the movement of the reversing switch 31 will energize the motor 26 and thereby operate the rods 18 and thus raise or lower the bar 17 and thus decrease or increase the tension and stretch of the fabric 14. It will also be apparent that the direction of the rotation of the motor 26 and consequently the direction of change in tension and stretch of the fabric 14 depends upon the direction in which the reversing switch 31 is moved in closing the motor current.

The operation of the reversing switch 31 is controlled by means adapted to so actuate the reversing switch as to produce continuously uniform stretch in the fabric 14. This means comprises a pair of rolls 36 positioned ahead of the tensioning devices 15 and a pair of rolls 37 positioned beyond the calender rolls. The rolls 36 and 37 are driven by the fabric web and each set of rolls is geared together by means of suitable gears 38 and 39 respectively. The lower rolls in the two pairs are provided with shafts 40 and 41 carrying bevel gears 42 and 43 respectively. The gear 42 meshes with a cooperating bevel gear 44 carried by a shaft 45 bearing a finger 46 which is electrically connected by a conductor 47 to one terminal of a source of power 48 the other terminal of which is connected by a conductor 49 to one terminal of each of the solenoids 32 and 33. The bevel gear 43 meshes with a cooperating bevel gear 50 carried by a shaft 51 which in turn carries an insulated disc 52 provided with a pair of contact segments 53 and 54 separated by the insulating segment 55 and connected respectively to slip-rings 56 and 57 on which bear brushes 58 and 59 connected by conductors 60 and 61 to the remaining terminals of the solenoids 32 and 33 respectively. The shafts 45 and 51 are geared to the shafts 40 and 41 by gear sets of such ratio that the proportion between the ratio of the set 50-43 and the ratio of the set 44-42 is the proportion of stretch which is desired in the fabric 14. It will be apparent that so long as this proportion of stretch is being imparted to the fabric, in other words so long as the fabric is stretched in its passage through the machine to an amount exactly compensated for by the difference in said gear ratios, the shafts 45 and

51 will rotate at the same speed, the finger 46 will remain on the insulating segment 55, no current will be imparted to either of the solenoids 32 or 33, the electromagnetic 5
6 reversing switch 31 will remain in neutral position, and the motor 26 will not be energized. It will also be apparent that should the shaft 51 rotate at a different speed than the shaft 45 the finger 46 will engage either 10
10 the segment 53 or the segment 54 to thereby energize either the solenoid 32 or the solenoid 33 and thus close the reversing switch 31 in one direction or the other to thereby energize the motor 26 and raise or 15
15 lower the bar 17 and thus impart greater or less stretch to the fabric 14. Different proportions of stretch are secured by changing the proportion of the ratios between the two gear sets, for example by changing the gear 20
20 set 50—43.

The disclosure herein is illustrative only and my invention is, of course, not limited thereto.

I claim:

- 25 1. A continuous stretching device comprising means adapted to continuously impart longitudinal tension to a moving web, means to vary the action of said tension imparting means, means to measure the amount of stretch in the web, and means controlled by said measuring means for controlling said varying means to thereby hold constant the amount of stretch in the web.
- 30 2. A continuous stretching device comprising means adapted to continuously impart longitudinal tension to a moving web, pairs of measuring rolls positioned on opposite sides of said means, to measure the amount

of stretch in the web, and means controlled by said measuring rolls to vary the tension 40 imparted by said first named means to thereby hold constant the amount of stretch in the web passing between the measuring rolls.

3. A continuous stretching device comprising means adapted to continuously impart 45 longitudinal tension to a moving web, pairs of measuring rolls, positioned on opposite sides of said means and driven from the web, said measuring rolls being operatively connected together to measure a predetermined 50 amount of stretch in the web, and means controlled by said measuring rolls to vary the tension imparted by said first named means to thereby maintain such predetermined amount of stretch in the web. 55

4. A continuous stretching device comprising means adapted to continuously impart tension to a moving web, pairs of measuring rolls positioned on opposite sides of said means, and driven from the web, aligned 60 shafts geared respectively to said pairs of measuring rolls, the gear ratios being proportional to a predetermined amount of stretch in the web between said measuring rolls, whereby said shafts normally rotate 65 at equal speeds, and means positioned between the ends of said shafts and responsive to differential movement therebetween to vary the tension imparted to the web by said first named means to thereby maintain 70 said predetermined amount of stretch in the web.

In testimony whereof I have signed my name to the above specification.

WALTER S. FREEBURG.
